RANGE SURFACE UNIT

Eugene W. Beggs, Glen Ridge, N. J., assignor to
Westinghouse Electric & Manufacturing Com-
pany, East Pittsburgh, Pa., a corporation of
Pennsylvania

Application September 27, 1940, Serial No. 358,596

10 Claims. (Cl. 219—37)

This application is a continuation-in-part of my application, Serial No. 162,244, filed September 3, 1937.

My invention relates to range surface heating units and the like, and more particularly to a heating unit having a radiant heating element therein.

With those radiant surface units known to the art having a heating element located in direct or indirect contact with the heating plate or surface, the heating element is generally of a high-cold-resistance material. The heating element, due to its high-cold-resistance, large mass and high conduction and radiation losses, which prevail with those elements known to the art, comes up to heat slowly, resulting in an undesirable appreciable time lag between the initial application of current and the time at which the heating element and the associated heating surface arrive at their maximum desired operating temperature, and, due to the losses mentioned are relatively inefficient. Such range surface units are accordingly too slow in their operation in that they come to heat too slowly, and are also too expensive in that they are less efficient and are short-lived, due to oxidation of the heating element, requiring frequent replacements by reason of the heating elements burning out. It is, therefore, an object of my invention to provide a range surface unit, or the like, which will come up to the desired cooking temperature very quickly after the time of application of power to the heating element, and will cook more efficiently and cheaply, and to provide a heating element located therein which will have a small mass, and which may be operated either in vacuum or in a suitable atmosphere of inert gas at any desirable pressure, resulting in a long average life for such elements and heating units, as well as in a reduced cost thereof.

It is likewise old in the art to use a lamp or radiant element for heating purposes, in combination with a reflector located in such a position as to direct substantially all the heat radiated from such lamp in a predetermined direction. However, with those heating units of this type known to the art, the reflector must be open and the lamp exposed to permit convection of air from the lamp and for permitting ready replacement thereof. This condition makes it practically impossible to keep the reflector clean and polished throughout its life and to protect the lamp or radiant element from being broken due to the accidental splashing or dropping of moisture or liquids upon such lamp and reflector. Also, when using a glass-type lamp, the lamp may fail due to the softening and distortion of its glass bulb caused by the excessive heat within the area enclosed by the reflector when the open end is closed by the cooking utensil, or when cov-

ered by a secondary plate. It is, therefore, a further object of my invention to provide a heating unit having a reflector and heating element sealed therein in such a manner that the reflector and heating element will be protected from any foreign matter that the operator might spill upon the heating unit, and that such reflector and heating element will be protected from all mechanical injury while, at the same time, a suitable controlled atmosphere (inert or high-vacuum) is employed.

A further object of my invention is to provide a heating unit which will heat the central portion of the top plate or cooking surface quicker and to a higher temperature than the balance of said top plate and the support therefor, which guarantees a maximum amount of heat exchange between the top plate and a vessel located thereon, and ensures that only a minimum amount of heat will be conducted away from the top plate to the surrounding supporting member.

A further object of my invention is to provide a heating unit including a hermetically-sealed casing having a reflector supported therein and spaced from the walls thereof.

A further object of my invention is to provide a heating unit including a hermetically-sealed casing having a reflector supported therein and electrically insulated from the walls thereof.

A further object of my invention is to provide a heating unit including a hermetically-sealed casing having a reflector supported therein in such a manner that when the reflector expands and contracts, it will not stress the walls of the container.

A further object of my invention is to provide a heating unit including a hermetically-sealed container, one wall of said container providing a heating surface or hotplate, and a reflector arranged in the container so as to limit the flow of convection currents about the under side of the heating surface or hotplate.

A further object of my invention is to provide a range surface unit having a radiant heating element and a reflector located therein whereby the energy radiated downwardly from the heating element, the top plate, and a cooking vessel placed upon the top plate will be reflected upwardly and, therefore, conserve the dissipated energy from the heating element and increase the operating speed and efficiency of the unit.

A further object of my invention is to provide a range surface unit, or the like, which will operate with a minimum amount of downward radiation, resulting in cooler operation of the connections.

Other objects of my invention will either be pointed out specifically in the course of the following description of one form of device em-

bodying my invention, or will be apparent from such description.

In the accompanying drawings:

Fig. 1 is a plan view of a device embodying my invention with the top plate removed;

Fig. 2 is a sectional view of the device, taken along line II—II of Fig. 1;

Fig. 3 is a sectional view taken along line II—II of Fig. 1 showing a modification of the top plate;

Fig. 4 is a partial sectional view of the device shown in the preceding figures; and

Fig. 5 is a partial sectional view taken along line V—V of Fig. 2.

Referring to the accompanying drawings, I show a heating unit 11 comprising a sealed envelope 12 having a top portion 13 which may be used as the top plate or cooking surface of the unit, a reflector 14 located within the envelope, and a heating element 15 insulatedly mounted intermediate the reflector and the top plate of such envelope.

The envelope 12 comprises the top plate or cooking surface 13, a main body portion 18, and a bottom terminal plate 19 which may have eyelets 53 associated therewith for sealing leads or conductors thereto. The envelope 12 may be made of any suitable material which will be impervious to gases, and which will be easy to form and work. However, it is preferred that such envelope be made of cold-rolled or chrome steel. It is preferred that the main body portion 18 of the envelope 12 be cylindrical in shape, substantially as shown, with the top plate 13 being welded to the main body portion in any suitable manner to form a gas-tight seal therewith. The bottom terminal plate 19 may likewise be welded to the cylindrical body portion to form a gas-tight seal therewith and may have an aperture 21 located therein, through which the exhaust tube 22 may be inserted and attached thereto for forming the final seal of the envelope when it is desirable to evacuate such envelope. However, it is to be understood that the top plate 13 and the bottom plate 19 may be attached to the body portion in any desired manner.

The top plate or cooking surface 13 of the heating unit comprises a central deformed portion 23 and a rim portion 24. The top plate 13 is made of any suitable material which will be able to withstand operations at high temperatures for long periods of time, either continuously or intermittently, without serious oxidation or disintegration, and which will be capable of withstanding a sharp blow or a sudden change in temperature, such as the spilling of ice water thereon, without injury while at a high temperature.

The bottom or inner surface of the central portion 23 of the top plate 13 should be permanently conditioned, such as roughened, blackened, or both, so that the top plate will be capable of absorbing a maximum amount of heat energy.

The central portion 23 of the top plate 13 may be flat, although it is preferred that it be arched either concavely or convexly to prevent such top plate from warping and cracking with repeated operations.

The rim portion 24 of the top plate 13 may be of any shape desired. However, it is preferred that such rim be integral with the central portion, and that it have a vertical depending shoulder 25 with an exterior horizontal lip 26 associated therewith.

The reflector 14 comprises any suitable heat-resisting material having a high reflecting power for radiant energy, such as nickel or aluminum, and has a highly polished surface located upon the top and bottom thereof. The reflector 14 should be formed into a very shallow dish-shaped structure having smooth contours. The reflector may be formed by a spherical spinning in which the radius of curvature is substantially greater than the diameter of the top plate, although such reflector need not be a paraboloid. The focus of the reflector, if it should have one, would then be located at a point above the surface of the top plate 13. However, it is to be understood that the important features of such reflector 14 are its shallowness, smoothness of curvature, and its high degree of reflectibility. It is to be understood that, by having the reflector shallow and shaped like a dish with a smooth contour and a highly polished surface, substantially all the radiant energy striking such surface will be reflected toward the top plate, and that by having the dish as shallow as possible, the energy radiated downwardly will be reflected upwardly in a direct path rather than being reflected from one portion of the reflector to another before being reflected upwardly. Due to this reduction in the number of reflections, the efficiency of the reflector will be greatly increased, since the efficiency decreases with each additional reflection.

The periphery of the reflector 14 is spaced from the heating surface or top plate 13 for reasons more fully explained hereinafter, but the periphery is placed as close as practical to the heating surface or hotplate so as to obstruct and hinder the heated gas that would tend to pour over the periphery of the reflector during the heating-up period. If this heated gas is not obstructed in some manner it will pour over the periphery of the reflector during the heating-up period and will set up convection currents which will circulate between the reflector and heating surface or hotplate. These convection currents would take an appreciable amount of heat away from the heating surface or hotplate. Preferably, no portion of the reflector is further from the hotplate or heating surface than one-fourth the diameter of the hotplate or heating surface.

One reason for spacing the reflector 14 from the walls of the envelope 12 is to prevent cracking of insulators 34 and 48, the glass-to-metal seals 20, and opening up of the welded joints in the envelope by the expansion and contraction of the reflector. During the heating-up period the reflector expands very rapidly, and if, during this period, the periphery of the reflector contacts the side walls of the envelope 12, this expansion of the reflector will stress the bushings 34 and 48, the seals 20, and the welded joints in the container. These stresses would tend to crack the bushings and the seals, and open up the welded joints in the container, thereby exposing the inside of the container to the atmosphere which would cause the tungsten filament heating elements to oxidize and burn out, and would also cause the reflector to tarnish and thereby lose its reflecting qualities.

The heating unit 15 may comprise one or more heating elements; however, it is preferred that such unit be comprised of a primary and a secondary filament 30 and 31, respectively, which should be supported substantially parallel to the top plate 13. The filaments 30 and 31 are comprised of tungsten wire or any other similar

material which can be operated at a high incandescent temperature, substantially 2500° C., which will not sag or evaporate appreciably when so heated, and which has a low-cold-resistance, permitting such filaments to come up to operating temperature almost instantly upon the application of power thereto. In forming the filaments, the tungsten wire or other suitable material, due to its ability to operate at a high incandescent temperature, may comprise small-diameter wire which may be helically wound and the helix formed into a circle having an overall length substantially shorter than the elements of the heating units now known to the art. The heating element may then be supported substantially horizontally and within a relatively short distance from the bottom of the top plate, permitting a maximum amount of direct radiation to the top plate.

The filaments 30 and 31, being comprised of tungsten or any other similar material which resists sag at high temperatures, need be supported at only a few points by a plurality of fingers 32 and 33, respectively, which may be rigidly mounted within any suitable insulator 34. By having the number of supporting fingers reduced to a minimum, it will be apparent that the energy conducted away from the filaments through such fingers will likewise be a minimum, ensuring the high percentage of radiant energy desired in the device embodying my present invention. Although I have shown and described the fingers 32 and 33 for supporting the filaments 30 and 31, it will be understood that the filaments may be supported in the envelope 12 by any satisfactory means.

The primary filament 30, as hereinabove described, is formed in an almost complete circle, and preferably has a diameter substantially two-thirds that of the top plate 13, while the secondary filament 31 is of similar shape, being coaxially mounted slightly below the plane of the primary filament, and having a diameter preferably substantially one-half that of the top plate 13. However, it is to be understood that the size and shape of the filaments may be varied depending upon the desired power rating of the heating unit, and that such unit may have any number of filaments connected to a power supply in any suitable manner.

The heating unit 11, as embodied in my present invention, may be assembled by having the reflector 14 attached to the bottom plate 19, by means of one or more suitable support members 38 which may be inserted through and rigidly attached to the reflector 14. The supports 38 are very slender so that when the reflector 14 expands, they will easily bend, and consequently will set up a minimum amount of stress in the walls of the envelope 12. The reflector is electrically insulated from the supports 38 and the envelope 12 by insulators 54 of lava or other suitable insulating material. The insulators 54 include a bushing member 52 and a ring-like member 58. It is important that the reflector 14 be electrically insulated from the envelope 12, so that in case one of the heating filaments should break and fall down on the reflector a short circuit will not be set up through the envelope 12.

A main insulator 34, which may be of lava or other suitable material may be located substantially in the center of the reflector 14 and may be attached thereto by having a tongue portion 39 thereof inserted through an aperture 40 located within the reflector 14, and by having a shoulder

portion 41 resting upon the top surface of the reflector. The insulator 34 may then be held rigidly within the aperture 40 by means of a plurality of suitable support members 42 rigidly attached to the top portion 43 of the insulator and to the reflector 14. However, it is understood that the insulator 34 may be mounted by any other desirable method.

Rigidly attached to the top of the main insulator 34 are a plurality of fingers 32, which may be attached thereto in any suitable manner. These fingers 32 are bent substantially horizontally or normally to the axis of rotation of the reflector, and having the free ends thereof wound into a small loop within which the primary filament may be loosely mounted. The fingers 32 comprise small-diameter wires, preferably of molybdenum, or any other suitable refractory material, so that such fingers may have the small loop readily formed about the filament 30, ensuring minimum heat drain therefrom with no danger of melting or fusing thereto, and so that the free ends of such fingers will be capable of flexing relatively to the insulator to cushion any mechanical jar or vibration which would otherwise injure the filament.

The secondary filament 31 is flexibly supported in a similar manner by a plurality of small fingers 33 which are preferably rigidly attached to the bottom surface of the top portion 43 of the main insulator 34. It is, therefore, obvious that the filaments 30 and 31 will be flexibly mounted, in such a manner that they may expand and contract without distortion, and that such filaments will be protected against mechanical vibrations or shock which would otherwise injure them.

The filaments 30 and 31 may be connected to a power supply through any suitable in-lead construction comprising a plurality of terminals 45, lead wires 46, in-leads 47, and glass-to-metal seals 20. The terminals 45 may be insulatedly mounted upon the top surface of the reflector by grommets 48 of lava or other suitable material inserted through small apertures 49 within the reflector and attached thereto. The lead wires 46 may then be rigidly attached to the terminals 45 and the insulating grommets 48 in such a manner that such lead wires 46 will be properly supported without the aid of additional supports.

The in-leads 47 may be of molybdenum or other suitable material and after being inserted through and attached to the eyelets 53 by means of the glass-to-metal seals 20 may be clamped or welded to the lead wires 46 ensuring an insulated gas-tight connection between the filaments 30 and 31 and any suitable power supply (not shown). A ceramic-to-metal seal may be used instead of the glass-to-metal seal 20 if so desired.

The eyelets 53 may be of such material and shape that they may be welded or otherwise attached to the bottom terminal plate 19 to form a gas-tight connection therewith, and also form a gas-tight metal-to-glass seal insulatedly between said eyelets and in-leads 47.

In view of the intense heat developed by the filaments, it is preferred that the terminals 45 and the lead wires 46 attached thereto be composed of nickel, molybdenum or some other suitable material. If it be preferred, the bottom portion of the terminals 45 may be extended downwardly and towards the center to form the lead wires where they may be operatively associated with the in-leads 47.

If it be desired, a plurality of plugs 44 operatively associated with the in-leads 47 may be

insulatedly mounted upon the bottom plate 19 for enabling the heating unit 11 to be removably mounted upon and attached to any range having a receptacle to cooperate therewith. The plugs 44 may be insulatedly mounted upon any suitable cups 49 by means of insulating grommets 50. The cups 49 may be rigidly attached to the bottom plate 19 about the eyelets 53 in any suitable manner. The plugs 48 may be connected to the in-leads 47 by means of a flexible wire 51 which will insulate the in-lead from any mechanical jar or vibration which might otherwise be transmitted from the plug 48 to the in-lead 47, resulting in a rupture between said in-lead and its glass-to-metal seal 20.

It is, therefore, obvious that the reflector, and the filaments insulatedly mounted thereon as a unit, may be used with any top plate or may be located within any suitable envelope, that due to the in-lead construction having a vacuum seal with the bottom plate, such envelope may be evacuated or may have a predetermined inert atmosphere located therein, and that due to the plugs being located upon the bottom plate and operatively associated with the filaments, such heating unit may be readily interchangeably mounted upon any range having a suitable receptacle associated therewith.

By having the heating element 15 and associated reflector 14 located within an envelope 12 which may be sealed and evacuated, or filled with an inert gas, the life of the filaments 39 and 31 may be greatly increased over those filaments which operate in an oxidizing atmosphere.

The top plate 13 may have the central portion 23 thereof deformed, as hereinabove described. By having the central portion deformed in the form of an arch, the plate may be unevenly heated without injury since the central portion of the deformation will be increasingly deformed, or in other words, the arch will become deeper and as the top plate cools, the deformation will return to its original position.

In operating the heating unit as hereinabove described, the filaments are connected to a power supply by any suitable switching means. Due to the low-cold-resistance of the filaments, the temperature of the filaments will instantly increase from the ambient to substantially 2500° C., and will cause substantially all of the electric power supplied thereto to be radiated therefrom in the form of heat energy. Approximately fifty per cent of the energy radiated from the heating elements will be radiated upwardly and the major portion of such energy will be absorbed by the heat-absorbing bottom surface of the top plate. However, that portion of the energy radiated upwardly that has not been absorbed by the top plate will be reflected downwardly. Such energy downwardly reflected from the top plate will contact the reflector, which, due to the highly polished top surface and the shallowness thereof, will efficiently reflect this energy back to the top plate in a direct path where the greater portion will be absorbed. However, a small portion of the re-reflected energy will again not be absorbed by the top plate but will be re-reflected by such top plate and reflector as hereinabove described until all of such energy, except the small amount absorbed by the reflector, is absorbed by the top plate. This ability to re-reflect the unabsorbed energy is especially important when the central portion of the top plate has an appreciable reflection factor, for it insures that a maximum amount of the energy dissipated by the filaments

will eventually be absorbed by the top plate, and further serves to insulate the space below the heating unit from such dissipated heat energy. Further, the highly polished under surface of the reflector tends to prevent the heat absorbed by the reflector from being radiated downward into the body of the envelope 12, thus further increasing the efficiency of the unit.

The balance of the radiant energy dissipated by the filaments not directly radiated upwardly will be radiated substantially downwardly in such a manner that it will contact the highly polished surface of the reflector, where, due to such reflector surface, the energy will be reflected directly upwardly upon the top plate. The greater portion of the reflected energy will be absorbed by the plate, however, a portion will be re-reflected downwardly to be again directly reflected back up against the top plate, as hereinabove described. Accordingly, it is obvious that that portion of the radiant energy not absorbed by the bottom surface of the top plate will be directly re-reflected back and forth between the reflector and the top plate until the top plate absorbs substantially all the energy emitted by the heated filament.

When a vessel is placed upon a heating unit as hereinabove described, the energy absorbed by the top plate will be radiated, conducted and convected from the top plate to the bottom of the vessel. Should the bottom of the vessel be blackened or dirty, a greater portion of this energy will be immediately absorbed while the remainder will be reflected downwardly towards the heating unit and will be re-reflected up to the bottom of the vessel by the reflector, and this cycle will continue until substantially all the energy dissipated by the heating element is absorbed by the bottom of the vessel.

It is, therefore, obvious that the top plate will radiate energy both upwardly and downwardly, while functioning as a transfer agent, as well as serving as a mechanical protective medium for the heating element and reflector surface located within the surface unit.

It is to be understood that for high speed and efficiency of the unit as a whole, the distance between the top of the reflector and the bottom of the top plate should be reduced to a minimum, and the edge or rim of the reflector should be as close to the bottom of the top plate as practicable to prevent radiant energy from coming into direct contact with the vertical sides 25 of the top plate and to muffle the escape of heated gas into the body of the envelope 12, thus diverting some of the energy which otherwise would be directed to the bottom of the top plate.

Various modifications may be made in the device embodying my invention without departing from the spirit and scope thereof, and I desire, therefore, that only such limitations shall be placed thereon as are imposed by the prior art and the appended claims.

What I claim is:

1. A heating unit comprising a hermetically-sealed metal container having a wall providing a hotplate or heating surface, hermetically-sealed terminals projecting through a wall of the container, a plurality of heating elements exposed in said container and disposed closely adjacent the heating surface in planes substantially parallel thereto but in spaced relation thereto and dissipating heat thereto primarily by radiation, a metal reflector disposed within the container closely adjacent the heating elements

on the side thereof remote from the heating surface, said reflector being substantially coextensive with the heating surface and spaced from the walls of the container, a metal support for supporting said reflector from a wall of the container, means electrically insulating said reflector from said support, said reflector and said supporting means being constructed and arranged so that the reflector when it expands will not stress the walls of the container, means for supporting the heating elements in the container, and conductors disposed within the container and connecting the heating elements with the terminals.

2. A heating unit comprising a hermetically-sealed container having a wall providing a hot-plate or heating surface, hermetically-sealed terminals projecting through a wall of the container, a plurality of heating elements exposed in said container and disposed adjacent the heating surface but in spaced relation thereto and dissipating heat thereto primarily by radiation, a reflector disposed within the container adjacent the heating elements on the side thereof remote from the heating surface, said reflector being substantially coextensive with the heating surface and having its periphery spaced from the walls of the container, a plurality of slender resilient rods supporting said reflector from a wall of the container, said resilient rods permitting said reflector to expand and contract without stressing the walls of the container, means for supporting the heating elements in the container, and conductors disposed within the container and connecting the heating elements to the terminals.

3. A heating unit comprising a hermetically-sealed container having a wall providing a hot-plate or heating surface, hermetically-sealed terminals projecting through a wall of the container, a plurality of heating elements exposed in said container and disposed adjacent the heating surface in planes substantially parallel thereto but in spaced relation thereto and dissipating heat thereto primarily by radiation, a metallic reflector disposed within the container closely adjacent the heating elements on the side thereof remote from the heating surface, said reflector being substantially coextensive with the heating surface and having its periphery spaced from the walls of the container, means for supporting the reflector from a wall of the container, said reflector and said supporting means being constructed and arranged so that the reflector when it expands will not stress the walls of the container, means for supporting the heating elements in the container, and conductors disposed within the container and connecting the heating elements with the terminals.

4. A heating unit as claimed in claim 3 wherein the peripheral portion of the reflector is inclined toward the peripheral portion of the heating surface.

5. A heating unit comprising a top plate, a plurality of helically wound heating elements ring-like in form disposed in planes each substantially parallel to said plate, the periphery of one heating element enclosing a larger area than that of the other, a shallow reflector disposed close to said elements, a central supporting structure stationarily mounted with respect to said reflector, and means comprising a plurality of widely spaced fingers mounted upon said supporting structure for supporting the respective heating elements, both elements being disposed to radiate

heat directly to said top plate and to said reflector.

6. A heating unit comprising a top plate, a plurality of helically wound heating elements ring-like in form disposed in planes each substantially parallel to said plate, the periphery of one heating element enclosing a larger area than that of the other, a shallow reflector disposed close to said elements, a central supporting structure mounted on said reflector, and means comprising a plurality of widely spaced fingers mounted upon said supporting structure for supporting the respective heating elements, both elements being disposed to radiate heat directly to said top plate and to said reflector.

7. A heating unit comprising a top plate, a plurality of helically wound small-diameter heating elements ringlike in form disposed in planes each substantially parallel to said plate, the periphery of the heating element closer to said plate enclosing a larger area than that of the other, a shallow reflector disposed close to said other heating element, a central supporting structure mounted on said reflector, and means comprising a plurality of widely spaced fingers mounted upon said supporting structure for supporting the respective heating elements, both elements being disposed to radiate heat directly to said top plate and to said reflector.

8. A heating unit comprising a hermetically-sealed container provided with a top plate providing a heating surface, a plurality of helically wound heating elements disposed in said container in planes each substantially parallel to said plate, and adjacent thereto, the perimeter of one heating element in one plane falling entirely within the projected area of the other, a shallow reflector disposed close to and under said elements within said sealed container, a centrally disposed supporting structure, and a plurality of widely spaced fingerlike supports carried by said supporting structure within said sealed container for supporting the respective heating elements in position to radiate heat directly to said top plate and to said reflector.

9. A heating unit as claimed in claim 8 wherein the reflector is spaced from the walls of the container.

10. A heating unit comprising a hermetically-sealed container having a wall providing a hot-plate or heating surface, hermetically-sealed terminals projecting through a wall of the container, a heating element or elements exposed in said container and disposed adjacent the heating surface and substantially parallel thereto but in spaced relation thereto and dissipating heat thereto primarily by radiation, a metallic reflector disposed within the container closely adjacent the heating elements on the side thereof remote from the heating surface, said reflector being substantially coextensive with the heating surface and having its periphery spaced from the walls of the container, means for supporting the reflector from a wall of the container, said reflector and said supporting means being constructed and arranged so that the reflector when it expands will not stress the walls of the container, means for supporting the heating elements in the container, and conductors disposed within the container and connecting the heating elements with the terminals.
